HAIR CURLER

Heliodoro Rubira, Jersey City, N. J.

Application April 25, 1940, Serial No. 331,659

4 Claims. (Cl. 132—40)

This invention relates to hair curlers and an object of the invention is to provide a device of this character which will facilitate the winding of the hair into small ringlets, and in accordance with the present invention a simplified and conveniently manipulatable hair curler is presented with means to facilitate the winding of the hair on the rotatable core of the curler into a coil or ringlet; and the invention together with its objects and advantages will be best understood from a study of the following description taken in connection with the accompanying drawings wherein—

Figure 1 is a side elevational view of one form of curler embodying the features of the present invention and with the parts in position after the strand of hair has been wound thereon into the form of a coil, the strands of hair not being shown.

Figure 2 is a view similar to Figure 1, but showing the parts of the curler arranged when initially engaging the strand of hair with the core of the curler.

Figure 3 is a sectional view taken substantially on the line 3—3 of Figure 1.

Figure 4 is a view similar to Figure 2 but illustrating a second form of the invention.

Figure 5 is a view similar to Figure 4 but illustrating a third form of the invention, and

Figure 6 is a longitudinal sectional view through a fourth form of the invention, certain parts being shown in elevation.

Referring more in detail to the drawings it will be seen that in each form of the invention the curler comprises a relatively short barrel 5 through which extends a rotatable rod or core 6, the same being equipped at one end thereof with a handle 7 of suitable design and structure that abuts one end of the barrel 5 and cooperates with a collar 8 fixed on the core or rod 6 and abutting the opposite end of the barrel 5, for holding the core rod 6 against longitudinal movement relative to the barrel 5 but leaving the core or rod free to rotate relative to said barrel 5.

At the free end thereof the core rod 6 is bifurcated to present a slot 9 with which the strands of hair, near the roots, are initially engaged for subsequently winding the strands in coil form on the slotted end 9 of the rod or core 6.

Further in accordance with the present invention there are provided for cooperation with the core 6 guide means that serve to confine the winding of the strands to such an extent that the strands will wind into a little coil of relatively small axial length. Thus, and in the form of the

invention shown in Figures 1 to 3 inclusive, such guide means include a pair of complementary disks 10 and 11 respectively.

The disk 10 is in one piece while the disk 11 is substantially divided into complementary half-sections 12 and 13, respectively; disk section 12 being integral with one end of a longitudinally curved lever 14, while disk section 13 is preferably formed integral with one end of a similar lever 15.

The levers 14 and 15 are substantially channel-shaped in cross section so that the paralleling ends thereof conformably engage, as shown in Figure 1, the rod 6 when the disk sections 12 and 13 are brought into substantial edge-meeting engagement.

Also, the levers 14 and 15 adjacent the ends thereof remote from the disk sections are provided with pairs of ears 16 and 17, respectively, that cooperate, respectively with hinge ears 18 and 19, respectively, provided on diametrically opposite sides of the barrel 5 to receive hinge pins 20 and 21, respectively, whereby said levers are pivotally connected to the barrel 5.

The disk section-equipped ends of the levers 14 and 15 are urged toward one another and into engagement with the rod or core 6 through the medium of coil springs 22 provided as shown.

The disk 10 is connected with the arcuate or convex edge of the disk section 13 through the medium of a web 23 formed integral with the edges of the disk 10 and disk section 13.

In using this form of the device pressure is applied to the lever 15 for swinging the same, together with the associated disk section 13 and disk 10, to the position shown in Figure 2, when the strands of hair to be coiled, adjacent the roots thereof, are engaged in the slot 9 of the core. Pressure on the lever 15 is then released permitting the lever and associated parts to move to the position shown in Figure 1, disk 10 being provided with a slot 24 to accommodate the slotted end 9 of the core or rod 6. With the parts in the position shown in Figure 1, the barrel 5 is held between the fingers of one hand while with the fingers of the second hand the rod or core 6 is rotated for winding the strands of hair on the end 9 of the core or rod 6 between the confronting and paralleling disks 10 and 11 to the end that said strands are wound into the desired coil. When the strands of hair have been coiled in this manner on the rod or core 6, the parts are again swung to the position shown in Figure 2, permitting the coiled hair to be readily sleeved off of the end 9 of the rod.

In the form of the invention shown in Figure 4,

but a single lever, indicated by the reference numeral 15a, is employed and mounted on one end of this lever 15a are a pair of spaced parallel identical disks 10a and 11a, respectively, each of the disks being provided with a slot 25 to accommodate the slotted end 9 of the core 6.

In using this form of the invention, the lever 15 is first swung to the position shown in Figure 4, and the strands of hair initially engaged with the slotted end of the rod 6 after which the lever 15a is permitted to swing into position with the disk-equipped end thereof engaging the rod 6 and the slotted end of the rod being accommodated in the slot 25 of the disks 10a and 11a so that subsequent winding of the hair strands on the end 9a of the rod will be between the confronting disks 10a and 11a as is thought to be obvious.

Disks 10a and 11a are connected together and secured in spaced parallelism to move with the lever 15a as a unit through the medium of a connecting web 23a that is disposed diametrically opposite to the open ends of the slots 25 as shown.

In the form of the invention shown in Figure 5, the parts corresponding to the disk 10, or 10a, and the web 23, or 23a, are omitted, each of the levers 14b and 15b being equipped at the ends thereof engageable with the rod or core 6 with complementary half disk sections 12a and 13a. When using this form of tool it will be apparent that the disk sections 12a and 13a will be in edge-abutting position forming a complete disk against which the strands of hair will be wound on the rod or core end 9a into the form of a coil or loop.

In the form of the invention shown in Figure 6 each of the levers, therein indicated by the reference numerals 14c, 15c, is provided at the end thereof engageable with the core or rod 6 with a pair of spaced parallel half disk sections 11b and 10b, the section 11b being integral with a lever 40 and the disk section 10b being secured in spaced parallelism to the disk section 11b through the medium of a connecting web 23b integral with the convex or arcuate edges of the disk sections. In this connection it will be noted that in each instance the outer disk section 10b at its straight edge is suitably notched as at 26 to accommodate the slotted end 9 of the core or rod 6.

In using this form of tool, the levers 14c and 15c are pressed inwardly against the action of the springs 22 to spread the disk-equipped ends of the levers apart and leave the end 9 of the rod free to permit the strands of hair to be engaged therewith. After this has been accomplished, pressure on the levers 14c and 15c is released permitting the parts to assume the position shown in Figure 6, whereupon the rod 6 is then rotated for winding the hair strands on the end 9 thereof between the confronting disk sections in order to form the desired coil.

From the above it will be seen that with each form of the invention the hair may be readily engaged with the slotted end 9 of the rotatable core or rod, after which the guide disks are brought into position to confine the winding of the hair strands on said end 9 of the core or rod in order to form a coil of such strands. After this has been accomplished the levers are then pressed inwardly against the action of the springs 22 permitting the coil of hair to be easily removed from the slotted end of the rotatable rod or core.

It will thus be seen that a device of this character will facilitate the winding of hair strands into coils and that the use of the same will enable such winding of the hair into coils to be accomplished without requiring a high degree of skill.

It is thought that a clear understanding of the construction, operation, manner of use, and utility of a device of this character will be had without a more detailed description thereof.

Having thus described the invention what is 10 claimed as new is:

1. In a hair-curling device of the character described, a tubular barrel, a winding core extending longitudinally of the barrel and rotatable relative thereto, said core being equipped at one end 15 with a hair-accommodating slot, levers pivotally mounted adjacent one end thereof to said barrel at opposite sides of the latter, and hair-confining disks on one end of said levers, said disks being notched to accommodate the slotted end of said 20 core.

2. In a hair-curling device of the character described, a tubular barrel, a winding core extending longitudinally of the barrel and rotatable relative thereto, said core being equipped at one end 25 with a hair-accommodating slot, levers pivotally mounted adjacent one end thereof to said barrel at opposite sides of the latter, and hair-confining disks on one end of said levers, said disks being notched to accommodate the slotted end of said 30 core, and the disks being arranged on the respective levers to present a pair of opposing disks between which the hair is confined during the winding of the hair on the core incidental to a rotative movement of the core relative to said 35 barrel.

3. In a hair-curling device of the character described, a tubular barrel, a winding core extending longitudinally of the barrel and rotatable relative thereto, said core being equipped at one end with 40 a hair-accommodating slot, levers pivotally mounted adjacent one end thereof to said barrel at opposite sides of the latter, and hair-confining disks on one end of said levers said disks being notched to accommodate the slotted end of said 45 core, and the disks being arranged on the respective levers to present a pair of opposing disks between which the hair is confined during the winding of the hair on the core incidental to a rotative movement of the core relative to said barrel, and 50 springs connected with said barrel and said levers at the pivoted ends of the latter normally biasing the disk-equipped ends of the levers towards one and another and into intimate engagement with the slotted end of said core.

4. In a hair curler of the character described, a barrel, a winding core extending longitudinally through the barrel and rotatable relative thereto, said core having a hair-accommodating notch in one end thereof, and manipulative hair-confining means cooperable with the notched end of the core for confining the hair-winding operation to substantially the notched end of said core, said hair-confining means embodying a spring-pressed lever pivotally mounted adjacent one end thereof 60 on said barrel, and a hair-confining instrumentality on the opposite end of said lever movable therewith into and out of position relative to the notched end of said core.

HELIODORO RUBIRA.
